UNITED STATES PATENT OFFICE

GEORG KÖNIG, OF BERLIN-DAHLEM, GERMANY

PENCIL SHARPENING DEVICE

Application filed November 1, 1928, Serial No. 316,459, and in Germany November 12, 1927.

The present invention relates to a device for sharpening pencils combined with a receptacle intended to catch the shavings or chips resulting from sharpening, the object being to provide an improved device of this kind which is convenient and easy to handle, inexpensive to manufacture, and adapted to permit the sharpener to be used at different working angles with relation to the receptacle or base part on which it is mounted.

According to the present invention this is achieved by mounting the sharpener by a universal joint on a base part formed as a receptacle for catching the shavings and chips, said joint enabling the sharpener to perform swinging motions only but not allowing the same to rotate about its own axis.

A further feature of the present invention is the provision of eyes formed in lugs in an opening of the receptacle by appropriate stamping and bending operations therein; these eyes forming bearings for a hinged frame in which the sharpener itself is pivoted.

The cost of manufacture may be reduced by manufacturing said frame from a strip of sheet metal and pressing up the trunnions or pins of the universal joint therefrom, said pins being journaled in the eyes on the receptacle and in the sharpener itself.

One example of an embodiment of the invention will now be described by way of example with reference to the accompanying drawings, in which:

Fig. 1 is a perspective view of the sharpener.

Fig. 2 is a side elevation of the sharpener member per se.

Fig. 3 is a rear elevation of the receptacle.

Fig. 4 is a side elevation of the same.

Fig. 5 is a top plan view of the receptacle.

Fig. 6 is a sectional view taken substantially on line 6—6 of Fig. 1 through the frame for pivotally supporting the sharpener member.

Fig. 7 is a side elevation of the same.

Referring now more particularly to the drawings, 1 is a supporting base, which is cup-shaped and serves also as a receptacle for the shavings and chips resulting from sharpening. 2 is a sharpening device or member pivotally supported for lateral swinging movements in an open oblong rectangular frame 3, which, in turn, is pivotally mounted for swinging movements in a vertical plane in eyes 4 provided in lugs 5 formed on the receptacle. As shown in Fig. 2, the sharpening device or member 2 comprises a slotted metal body or shoe provided with a tapered bore 6 and a cutter 7.

The receptacle 1 is formed at one side with an opening intersecting its rim edge, and the lugs 5 are formed by parts of the metal displaced to provide said opening. The frame 3 is arranged in the opening between the lugs 5, and the sharpening device or member 2 is mounted in and enclosed by said frame and projects inwardly beyond the said opening into the receptacle.

As shown particularly in Figs. 6 and 7, the frame 3, which is made from a strip of sheet metal bent into form, is provided with pressed out trunnions or joint pins 8 and 9, by means of which the frame is pivoted in the eyes 4 of the lugs 5. The frame is also provided with pressed out trunnions or joint pins 10 and 11 engaging in corresponding sockets or openings in the sharpening device 2, whereby the latter is pivotally mounted in said frame.

As will be evident from the foregoing description, the sharpening device is, by its pivotal connection with the frame 3, and the pivotal connection of the latter with the supporting base or receptacle 1, universally jointed to said receptacle, so that said sharpening device is capable of performing swinging movements relatively to the receptacle in two directions or planes at right angles to each other. By this means the sharpening device is adapted to be adjusted to operate

at different angles, both vertically and laterally with relation to the receptacle, so that the sharpening operation may be performed at various working angles in an easy and convenient manner and under conditions which would otherwise be awkward and inconvenient.

Having thus described my invention, 1 claim:

- 10 1. A pencil sharpener consisting of a base portion, a frame pivoted on the base portion, and a sharpening device suspended from the frame to swing relatively thereto.
- 15 2. A pencil sharpener consisting of a base portion formed as a receptacle for pencil shavings, a frame hinged to the rim edge of said receptacle, and a sharpening device hinged to said frame.
- 20 3. A pencil sharpener consisting of a base portion formed as a receptacle for pencil shavings and having eyes at the rim edge thereof, a frame hinged to the eyes, and a sharpening device hinged to the frame.
- 25 4. A pencil sharpener consisting of a base portion formed as a receptacle for pencil shavings, a plate metal frame having two sets of pressed-out joint pins, one set engaging the receptacle and pivoting the frame thereto, and a sharpening device in the frame and pivoted thereto by the other set of joint pins.
- 30 5. A pencil sharpener comprising a cup-shaped receptacle, and a sharpening device extending into said receptacle and swingingly jointed thereto.
- 35 6. A pencil sharpener comprising a receptacle, a sharpening device extending into the receptacle and pivoted thereto to swing in planes both vertically and laterally of said receptacle.
- 40 7. A pencil sharpener consisting of a receptacle, an open rectangular frame pivoted to the receptacle to swing in a vertical plane, and a sharpening device extending through and pivoted to said frame to swing laterally of the receptacle.
- 45 8. A pencil sharpener comprising a cup-shaped receptacle having an opening at one side and lugs bent outward at opposite sides of said opening, and a sharpening device extending through said opening into the receptacle and pivotally supported by said lugs to swing in planes vertically and laterally of the receptacle.
- 50 9. A pencil sharpener comprising a cup-shaped receptacle having an opening at one side intersecting its rim edge and provided with outwardly projecting lugs at the opposite sides of said opening, an open rectangular frame disposed in said opening and pivoted to said lugs to swing in a plane perpendicular to the plane of the receptacle, and a sharpening device extending through said frame and pivoted thereto to swing in a direction laterally of the receptacle.

10. A pencil sharpener, comprising a base member adapted to receive pencil shavings, and a sharpening device swingingly attached to said base member and with its discharge portion extending thereover.

11. A pencil sharpener, comprising a base member adapted to receive pencil shavings, and a non-rotatable sharpening device swingingly attached to said base member and with its discharge portion extending thereover.

In testimony whereof I affix my signature.

GEORG KÖNIG.
